BRACKET FOR A TERMINAL HOUSING OF AN ELECTRIC STRIP HEATER

Donald M. Cunningham, 2507 Greensburg Pike,
Pittsburgh, Pa. 15221

Filed Apr. 5, 1974, Ser. No. 439,224

Term of patent 14 years

Int. Cl. D8—08

U.S. Cl. D8—230

FIG. 1.

FIG. 2.

FIG. 1 is a perspective view showing one side of a bracket for a terminal housing of an electric strip heater, showing my new design, and

FIG. 2 is a perspective view showing the opposite side of the bracket.

I claim:

The ornamental design for a bracket for a terminal housing of an electric strip heater, substantially as shown.
